(57) **CLAIM**

The ornamental design for an water heater tray device, as shown and described.

DESCRIPTION

FIG. 1 is a top perspective view of a water heater tray device;

FIG. 2 is a bottom perspective view of a water heater tray device;

FIG. 3 is a front planar view of a water heater tray device;

FIG. 4 is a rear planar view of a water heater tray device;

FIG. 5 is a right side planar view of a water heater tray device;

FIG. 6 is a left side planar view of a water heater tray device;

FIG. 7 is a top view of a water heater tray device.

FIG. 8 is a bottom view of a water heater tray device; and,

FIG. 9 is a cross-section view of a water heater tray device,

The broken lines shown in the drawings represent unclaimed portions of the WATER HEATER TRAY DEVICE and form no part of the claimed design.
